United States Patent Office

Des. 190,700
Patented June 20, 1961

190,700

COMBINED MARKING PEN AND WELL OR SIMILAR ARTICLE

Nathan R. Cline, 752 S. Belmont, Wichita, Kans.

Filed Mar. 24, 1960, Ser. No. 59,862

Term of patent 14 years

(Cl. D74—1)

FIG. 1

FIG. 3

FIG. 1 is a front elevational view of a combined marking pen and well showing my new design.

FIG. 2 is a side elevational view thereof; and

FIG. 3 is an exploded perspective view thereof showing the sides opposite to those of FIGS. 1 and 2.

I claim:

The ornamental design for a combined marking pen and well or similar article, as shown.
